No. 749,274.

PATENTED JAN. 12, 1904.

S. C. DRAKE.
PLOW HANDLE CLAMP.
APPLICATION FILED APR. 1, 1903.

NO MODEL.

UNITED STATES PATENT OFFICE.

SEABORN C. DRAKE, OF WASHINGTON, GEORGIA.

PLOW-HANDLE CLAMP.

SPECIFICATION forming part of Letters Patent No. 749,274, dated January 12, 1904.

Application filed April 1, 1903. Serial No. 150,652. (No model.)

To all whom it may concern:

Be it known that I, SEABORN C. DRAKE, a citizen of the United States, residing at Washington, in the county of Wilkes and State of Georgia, have invented a new and useful Plow-Handle Clamp, of which the following is a specification.

The invention relates to improvements in plow-handle clamps.

10 The object of the present invention is to improve the construction of clamps for plow-handles and to provide a simple, inexpensive, and efficient one of great strength and durability adapted to be readily applied to a plow and capable of securely fastening the plow-handles to the plow-beam and of enabling the former to last as long as the latter.

15 The invention consists in the construction and novel combination and arrangement of parts hereinafter fully described, illustrated in the accompanying drawings, and pointed out in the claim hereto appended.

20 In the drawings, Figure 1 is a perspective view of a portion of a plow-beam and plow-handles provided with a handle-clamp constructed in accordance with this invention. Fig. 2 is a side elevation of the same. Fig. 3 is a transverse sectional view on the line 3-3 of Fig. 2. Fig. 4 is a detail perspective 25 view of one of the clamps.

30 Like numerals of reference designate corresponding parts in all the figures of the drawings.

35 1 designates a plow-beam to the rear end of which are secured handles 2, arranged at opposite sides of the beam and supported by opposite clamps 3. The handles are arranged at an inclination in the usual manner and are secured to the beam by means of transverse 40 bolts 4, which also fasten the clamps to the plow and which are provided with nuts of the ordinary construction; but any other suitable fastening devices may be employed for securing the handles and the clamps to the plow-beam.

45 Each clamp, which is reversible and adapted to be used on either side of the plow-beam, is arranged at an inclination to conform to the inclination of the plow-handle and is composed of a plate and side flanges 5 and 6, and

the upper edges of the plate which forms the outer side face are horizontal. The lower edges are arranged in the same plane as the lower face of the plow-beam and the lower ends of the plow-handle, and the upper end 55 of the clamp is extended above the plane of the upper face of the plow-beam, as clearly shown in Fig. 2.

55 The front side flange 5 is provided with an integral laterally-extending lug or arm 7, projecting inward from the lower end of the flange 5 and fitted in a socket of the plow-beam and arranged near the lower edge thereof. The inwardly-extending lug or arm 7 is rounded to fit a round bore or hole, and as 60 the pressure or strain at the front of the lower end of the clamp is upward there is no liability of the plow-beam splitting, and the socket or hole may be located close to the bottom of the beam.

65 The rear flange is provided at its upper end with the laterally-extending lug or arm 8, rounded similar to the inwardly-extending lug or arm 7 and arranged upon the upper face of the plow-beam, as clearly illustrated 70 in Figs. 2 and 3 of the accompanying drawings. The clamps are provided with perforations for the reception of the bolts, and these perforations may be square to receive the squared portion of the bolt adjacent to the 75 head of the same, or, if desired, the perforations of one plate may be square and the others round to fit the rounded portion of the bolts adjacent to the nuts. The upper end 9 of the front flange and the lower end 10 of the rear 80 flange are cut away or beveled, as shown, and the other ends of the flanges, which are provided with the arms or lugs, are enlarged adjacent to the same to strengthen the structure to prevent any liability of the lugs or arms 85 breaking off at the inner side edges of the flanges.

90 It will be seen that the plow-handle clamps are exceedingly simple and inexpensive in construction, that they are adapted to be readily applied to a plow, and that they are capable of supporting the handles at the points where they are attached to the beam and where they break when unsupported. It will also be clear 95 that by supporting the plow-handles as shown 100

and described they are adapted to withstand severe strains and are enabled to last as long as the plow-beam.

What I claim is—

- 5 A plow-handle clamp comprising a plate having side flanges disposed at right angles thereto and extended the entire length of said plate, each flange having a stud disposed at one end thereof and the other end beveled, 10 said studs being disposed at diagonally-oppo-

site points and projecting beyond the flanges to engage a plow-beam.

In testimony that I claim the foregoing as my own I have hereto affixed my signature in the presence of the witnesses.

SEABORN C. DRAKE.
